UNITED STATES PATENT OFFICE.

RAY E. KELLOGG, OF NEEDLES, CALIFORNIA.

AUTOMATIC PROPELLER.

1,036,122.

Specification of Letters Patent. Patented Aug. 20, 1912.

Application filed October 21, 1910. Serial No. 588,342.

To all whom it may concern:

Be it known that I, RAY E. KELLOGG, citizen of the United States, and residing at Needles, in the county of San Bernardino 5 and State of California, have invented certain new and useful Improvements in Automatic Propellers, of which the following is a specification.

My invention relates to improvements in 10 propellers for aerial propulsion, or for use in connection with vessels for water navigation.

The invention has for its object to provide for controlling or regulating the pitch 15 or angle of the propeller-blades in accordance with the speed or flight of the aeroplane, and thus providing for equalizing or proportioning the air-pressure upon the propeller-blades with the centrifugal force.

20 A further object of the invention is to carry out the aforesaid end in a simple, inexpensive and effective manner.

The invention consists, primarily, of certain instrumentalities or features substantially as hereinafter fully disclosed and defined by the claims.

In the accompanying drawing, illustrating the preferred embodiment or disclosure 30 of my invention, which disclosure may be changed or varied as circumstances or conditions may suggest, without departing from the spirit thereof,—Figure 1, is a view in elevation of the invention, partly in section. Fig. 2, is a transverse section produced 35 through one of the blades or wings of a propeller. Fig. 3, is a detail view, showing a modified or differential form of propeller-blades, including centrifugal ball governors therefor, the blades being shown in end elevation. Fig. 4, is a plan view of another 40 form of the disclosure of my invention. Fig. 5, is a like view of another disclosure or modification of the invention.

In practising my invention, I apply to 45 the usual driving or main shaft, 1, of the motor (not shown), a transverse shaft 2, having formed centrally thereof a sleeve, or circular formation 3, for the reception of the main-shaft, and upon which shaft said 50 sleeve is tightly fitted or fixed as will be learned from Fig. 1. Blades or wings 4—4, are each formed with a longitudinal tubular 55 formation or passage 5, receiving the transverse shaft 2, said blades or wings being arranged upon opposite sides of the sleeve 3, or point of intersection of the shaft 1,

with the transverse shaft 2, and adapted to turn thereon a greater or less extent by carrying their angle of presentation to the air-pressure or line of travel, as will presently more fully appear. These wings or blades are in cross-section of the outline disclosed by Fig. 2, being approximately elliptical, or tapered in curved lines toward each longitudinal edge, and increasing in 65 width toward their outer ends. The wings or blades are each formed with a greater and a lesser cross-sectional portion or arm laterally or at opposite sides of the shaft 2, this arrangement of the wings or blades being reversed at opposite sides of the shaft, as clearly disclosed in Fig. 1, the greater or wider cross-sectional blade-portions forming the "follow" sides or rear of the blade, as relates to the direction of rotation, as 70 indicated by the arrow in Fig. 1. The blades or wings and their carrying shaft have spiral-threaded connection, as indicated at 6 and 7 and the shaft 2 is likewise provided with springs 8 which operate between 75 loose washers 9 and adjusting nuts 10 on the shaft, and thus hold the wings 4 yieldably in their inner position, whereby during the rotation of said shaft said wings or blades, by reason of centrifugal action, will have a 80 limited independent turning movement upon their carrying shaft and thus provide for changing the angle of presentation of said blades or wings, to the air-pressure. This has the result of controlling or regulating 85 such angle of presentation or pitch of said blades according to the speed or flight of the aeroplane, consequently providing for equalizing or proportioning the air-pressure upon said blades or wings to the centrifugal 90 force, which automatic adjustment is requisite for the perfect manipulation or handling of the aeroplane in transit or flight. The springs 9, when compressed by the outward movement of said blades or wings 100 under centrifugal action when the speed increases, automatically return the latter to their initial position when the speed is reduced. By manipulating said nuts, the tension of said springs, may be increased or 105 decreased and their pressure thus controlled upon the wings or blades.

In Fig. 3, are shown duplicate blades or wings 11, pivotally connected as at 12, to opposite sides of a collar or sleeve 13, fixed 110 to the motor or driving shaft 1, said blades or wings being formed similar to the blades

or wings shown in Figs. 1 and 2, and having rigidly connected thereto, near their outer ends, the inner ends of two opposite links 14, of a centrifugal governor 15, the other two links 16, of said governor having their outer ends pivoted to a sliding sleeve 17, fitted upon the motor-shaft, the other ends of the links 14, and 16, being connected to ball or weight members 18 of said governor.

10 Any increase of speed of the blades will correspondingly increase the pressure and cause them to endeavor to assume a position with their faces more nearly at right angles to the motor-driven shaft 1 and this movement is resisted by the centrifugal force exerted by the weights 18 and thus the "pitch" is equalized. The blades being revolved as they move very rapidly through the air as the forward speed increases the resistance on the blades decreases as the balls 18 will be moved farther apart until the resistance is again equal to the "pull" of the blades.

In the form of the invention illustrated in Fig. 4, the blades or wings have arms or links 20 connected to their inner ends at 19, at diagonally opposite corners thereof, and with fixed ball or weight members 21 connected thereto, the motor-shaft 1, in this instance having a T coupling or union connection 22, with the shaft 2. By means of this arrangement, is provided a propeller adapted to maintain the same thrust or pull, with the same number of revolutions at different speeds through the air.

In Fig. 5, is illustrated a form of the invention adapted more especially for use in connection with a boat or water navigation, and in this arrangement of the device 40 a main or motor-shaft 1, has applied thereto a tubular shaft or sleeve 23, slidable thereon and arranged in connection with a centrifugal governor 24, connected to said motor or main shaft. Said tubular shaft or sleeve 45 23, is upheld at one end and passed through a shorter sleeve or collar 24, having fixed thereto, or integral therewith, a disk-member 25, suitably abutting or fitting the inside of the stern of the vessel, the sleeve 50 or collar 24', being adapted to pass through the vessel shell at the stern and also through the sleeve 23, extending beyond said collar and the vessel shell. Propellers 25, are pivoted to the motor or main shaft 1, at one end 55 of the latter, and are connected, at the inner ends of their shorter arms to the outer ends of links 26, whose opposite ends are connected to the slidable sleeve or shaft 23, at its rear end.

60 Having thus described my said invention,

what I claim as new and desire to secure by United States Letters Patent, is:—

1. A device of the class described, comprising a motor driven shaft, other shafts extending transversely of said motor driven shaft, a blade rotatable upon each of said transverse shafts, a spiral threaded connection between each of said blades and its shaft, and resilient means operating to maintain said blades yieldably in normal 65 position.

2. A device of the class described, comprising a motor driven shaft, other shafts rotatable with said motor driven shaft, a blade rotatable upon each of said other 75 shafts, a spiral threaded connection between each of said blades and its shaft, and resilient means operating against each of said blades to automatically return the blades to normal position when the speed decreases. 80

3. A device of the class described, comprising a motor driven shaft, other shafts rotatable with said motor driven shaft, a blade rotatable upon each of said other shafts, a spiral threaded connection between 85 each of said blades and its shaft and holding the blades normally with their least pitch presented to the direction of motion under relatively slow speed and causing the pitch to be increased when speed is increased, and resilient means operating to maintain the blades yieldably in normal position and to automatically return them to normal position when the speed is decreased. 90

4. A propeller comprising a motor-shaft, blades or wings, shafts carrying said wings, a screw thread connection between each of said blades, and its shaft, and resilient means for returning said blades to initial 100 position.

5. A propeller comprising a motor-shaft, blades or wings, a shaft carrying said blades or wings, screw-threaded connection between 105 each of said blades and its shaft adapted to allow them to be set at an angle to the pressure delivered thereon, and springs applied to said wings or blades and their carrying shaft, and adjusting nuts engaging said springs, said springs operating to maintain the blades yieldably in normal position and to automatically return them to normal position when the blade is decreased. 110

In testimony whereof I affix my signature in presence of two witnesses.

RAY E. KELLOGG.
